UNITED STATES PATENT OFFICE.

GEORGE W. JACKSON, OF CHICAGO, ILLINOIS, ASSIGNOR, BY MESNE ASSIGNMENTS, TO BUCYRUS COMPANY, OF SOUTH MILWAUKEE, WISCONSIN, A CORPORATION OF WISCONSIN.

CONVEYER DEVICE FOR EXCAVATING AND LOADING MACHINES.

1,178,449.

Specification of Letters Patent.

Patented Apr. 4, 1916.

Application filed August 26, 1912. Serial No. 717,015.

To all whom it may concern:

Be it known that I, GEORGE W. JACKSON, a citizen of the United States, and a resident of Chicago, in the county of Cook and 5 State of Illinois, have invented certain new and useful Improvements in Conveyer Devices for Excavating and Loading Machines; and I do hereby declare that the following is a full, clear, and exact description there- 10 of, reference being had to the accompanying drawings, and to the characters of reference marked thereon, which form a part of this specification.

This invention relates to improvements 15 in conveyers for excavating and loading machines of that class provided with a series of spaced buckets or like devices which are carried, by the traveling movement of the conveyer, into the pile of material to be handled to pick up the material and there- 20 after carry the same to a place of disposal, as a car at the rear of the machine upon which the material is to be loaded and transported.

25 Among the objects of the invention is to provide means on the conveyer located between the buckets for loosening the material in the pile so that said material will not tend to be packed in the buckets when the 30 buckets are thrust into the pile, thereby permitting said material to be freely discharged from the buckets when the latter reach their dumping position.

A further object of the invention is to 35 provide means carried by the flexible side members or chains of the conveyer at the spaces between the buckets and at the sides of the buckets to prevent the material falling laterally off of the conveyer.

40 A still further object of the invention is to provide means carried by the side members or chains of the conveyer for cleaning the tracks of the boom on which the conveyer travels.

45 The invention consists in the matters hereinafter set forth and more particularly pointed out in the appended claim.

50 My invention is herein shown as applied to the conveyer of an excavating and loading machine of that general type shown in my prior application for United States Letters Patent, Serial No. 691,900, filed on the 19th day of April, 1912, but is adaptable to machines of other types.

In the drawings:—Figure 1 is a side elevation of an excavating and loading machine equipped with my improved conveyer device. Fig. 2 is a transverse section of the boom and the conveyer device. Fig. 3 is a detail transverse section showing the manner of mounting the loosening fingers on the conveyer. Fig. 4 is a detail plan view of one of the side chains of the conveyer, showing the manner of mounting the sweeping brush thereon. Fig. 5 is a section on the line 5—5 of Fig. 4. Fig. 6 is a transverse section on the line 6—6 of Fig. 4. Fig. 7 is a detail side view of another form of conveyer showing the application of the chain carried side bars thereto.

The boom 10 shown in Fig. 1 comprises a generally horizontal rear portion which extends to a point rearwardly of the frame or support 11 by which it is carried, and a downwardly curved front portion which extends to a point in front of the frame 11 in position to be forced into the pile of material to be handled. Said frame 11 in practice is provided with suitable traction means to advance and retract the machine 80 toward and from the pile of material. The said boom comprises side members 14, 14 which carry at their upper and lower edges inwardly extending flanges 15, 15 constituting tracks on which the conveyer chains are 85 supported and travel. Said side members may be connected by the upper and lower transverse plates 16 which extend between and are riveted to the side members. The upper plate prevents material from falling 90 through the boom.

The boom is supported at its rear end on the frame 11 by standards 18, 18 which are pivoted at their lower ends at 19 to lugs that rise upwardly from the frame 11. The 95 boom is also supported at the forward end of the frame by means of raising and lowering links, comprising the lower interiorly screw-threaded sleeves 20 pivoted at 21 to the frame, and the upper right and left 100 hand screw shafts 22 that are rotatively mounted at their upper ends in brackets 23 pivotally carried by a transverse shaft 24 that extends through the boom; the said transverse shaft and screw shafts being provided with intermeshing beveled gears 25, 26 whereby rotation of the shaft 24 is communicated to the screw shafts, to raise and 105

lower the boom. This construction is generally similar to the construction shown in my pending application for United States Letters Patent, Serial No. 713,214, filed on 5 the 5th day of August, 1912.

The conveyer comprises endless side chains 30, 30, each of which consists of laterally separated links 31, 31 that are joined by pins 32 that extend through their overlapping ends as shown in Fig. 4. Said pins 10 are equipped with rollers 33 that travel on the tracks 15. Extending between the said side chains and spaced longitudinally of the conveyer are a plurality of buckets 35, 35 15 which may be made of the general form shown in Figs. 1 and 2 or otherwise, said buckets being open at their ends in the direction toward which the conveyer travels. As herein shown, the buckets are connected 20 with the side chains by the pins or bolts 32 which connect the links of the chains together, said pins or bolts extending inwardly beyond the chains and through the side walls of the buckets and provided at their inner 25 screw-threaded ends, inside said walls, with nuts.

Arranged along the conveyer in the spaces 30 between the buckets are a plurality of loosening fingers 37, which are carried by the side chains 30 and extend outwardly therefrom to or approximately to the line of the scooping edges of the buckets. These fingers are arranged in sets, with five fingers in a set as herein shown, though a less or a greater 35 number may be employed. Each set extends transversely across the conveyer, and they are carried by plates 38 which are made of substantially the width of the bottoms of the buckets and are formed with outsanding 40 flanges 39, 39 which are pierced to receive the pins or bolts 32 of the conveyer chains, whereby said plates are carried by the conveyer chains in the same manner as are the buckets 35. The said flanged margins of 45 the plate 38 may be reinforced by angle bars 40, as shown in Fig. 3, said angle bars serving to strengthen the flanged margins of the plates 38. The said loosening fingers preferably extend rearwardly from the plates 50 and are curved upwardly and forwardly in the same general manner as the rear walls of the bucket. As herein shown, they are attached to the carrying plates 38 by means of rivets which extend through horizontally 55 arranged portions 42 that lie over the said plates 38 and angle bars 40. The said loosening fingers serve to loosen the material in advance of the attack thereof by the buckets, so that when the buckets are forced 60 into the material said material is loosened to such an extent as to avoid the packing thereof into the buckets as the buckets are forced into the material. In certain kinds of material which tend to pack or solidify, 65 such for instance as fertilizers, the forcing

of the buckets into the pile of material has the effect to pack the material solidly in the buckets so as to prevent the free clearance of the material from the buckets when the latter reach their dumping position. The 70 use of the loosening fingers described avoids such packing of the material in the buckets and enables the material to be dumped freely from the buckets.

In order to prevent the material from 75 dropping or falling laterally off the conveyer at the spaces between the buckets, the side chains of the conveyer are provided with upstanding retaining plates or members of substantial height which overlap the 80 side wall of the buckets. These retaining plates may comprise extensions 45, 45 of the inner link members 31 of the side chains, as best shown in Figs. 1, 2 and 3. As herein shown, the said link members extend upwardly substantially one-half of the height of the buckets. The end plates or extensions are turned outwardly to properly fit the flaring side walls of the buckets, as best shown in Figs. 2 and 3. As shown in Fig. 90 1, the buckets are spaced a distance apart equal approximately to three links of the chain, so that the inner members of these three links are thus widened to prevent the material from falling laterally off the conveyer at any point between the buckets, the end members overlapping the side walls of the adjacent buckets.

In Fig. 7 is shown a conveyer in which the buckets 35 are located closely adjacent 100 to each other. In this construction the inner member of each alternate link 48 extends across the space between adjacent buckets, with one end thereof overlapping a rear bucket and the other end thereof overlapping 105 a forward bucket.

In order to prevent the tracks 15 from becoming clogged by material which may drop off the buckets, I have provided brushes, designated as a whole by 50, which are carried by the side chains in position to sweep along the carrying surfaces of the tracks. These brushes each comprise a block 51 arranged between the members of the chain links, as best shown in Figs. 4 and 6, and 110 they are provided on their lower sides with bristles 52 adapted for sweeping engagement with the tracks, as best shown in Figs. 1 and 6. The said blocks 51 are preferably arranged diagonally across the space between the members of the chain links so as 115 to provide a maximum surface of brush contact with the tracks, and also to most effectively scrape material from the tracks.

In order to permit the brushes to swing 120 outwardly to clear the sprocket wheels about which the side chains are trained, said brushes are carried by spring arms 55, 55 which, in the present instance, are curved about the pins 32 on which the rollers 33

are mounted, and are attached thereto in the manner shown in Fig. 5; the rollers 33 adjacent to the brushes being somewhat shortened for the purpose of this attachment.

5 The conveyer side chains are trained about sprocket wheels 60, 61, mounted at the front and rear ends respectively of the boom. The conveyer is driven by a motor 62 carried by the rear end of the boom which is geared to the shaft 63 of the rear sprocket wheel 61, in the manner shown in Fig. 1.

10 It will be understood that the structural details herein shown may be somewhat varied within the spirit and scope of the invention, and the invention is not limited to such details except as hereinafter made the subject of specific claim and as imposed by the prior art.

I claim as my invention:—

20 A conveyer for excavating and loading machines comprising, in combination with a boom having conveyer tracks, of a conveyer comprising side chains which travel on said tracks, said chains each comprising laterally spaced articulated link members, buckets arranged between and carried by said chains, and brushes between the laterally spaced link members of said chains adapted for sweeping contact with said tracks.

25 In testimony, that I claim the foregoing as my invention I affix my signature in the presence of two witnesses, this 20th day of August, A. D. 1912.

30 GEORGE W. JACKSON.
